UNITED STATES PATENT OFFICE

149,577

DESIGN FOR A VEHICLE HOBBY HORSE

Justus G. McCoy, Milwaukee, Wis., assignor to
Ottolie Thurow, Milwaukee, Wis.

Application April 26, 1946, Serial No. 128,963

Term of patent 14 years

(Cl. D34—15)

To all whom it may concern:

Be it known that I, Justus G. McCoy, a citizen of the United States of America and a resident of Milwaukee, in the county of Milwaukee and State of Wisconsin, have invented a new, original, and ornamental Design for Vehicle Hobby Horse, of which the following is a specification, reference being had to the accompanying drawings, forming a part thereof.

In the drawings:

Fig. 1 is a side elevational view of the vehicle hobby horse showing the invention;
Fig. 2 is a top view of the hobby horse;
Fig. 3 is a front view of the hobby horse; and
Fig. 4 is a rear view of the hobby horse.

I claim:

The ornamental design for a vehicle hobby horse, as shown.

JUSTUS G. MCCOY.
